DESIGN FOR A WEATHER STRIP

Forrest F. Beil, Clinton, Iowa, assignor to Curtis Companies Incorporated, Clinton, Iowa, a corporation of Iowa

Application October 12, 1942, Serial No. 108,507

Term of patent 14 years

To all whom it may concern:

Be it known that I, Forrest F. Beil, a citizen of the United States and a resident of Clinton, in the county of Clinton and State of Iowa, have invented a new, original, and ornamental Design for a Weather Strip, of which the following is a specification, reference being had to the accompanying drawing, forming a part thereof,

I claim:

The ornamental design for a weather strip, substantially as shown.

FORREST F. BEIL,
